(57) **CLAIM**

The ornamental design for an ice skating trainer, as shown and described.

DESCRIPTION

FIG. 1 is a perspective elevational view of an ice skating trainer showing my design;

FIG. 2 is a front elevational view thereof;

FIG. 3 is a rear view thereof;

FIG. 4 is a left side elevational view thereof;

FIG. 5 is a right side elevational view thereof;

FIG. 6 is a top elevational view thereof; and,

FIG. 7 is a bottom view thereof.

The broken lines in the drawings depict portions of the ice skating trainer that form no part of the claimed design.
